UNITED STATES PATENT OFFICE

2,516,898

PRIMER AND METHOD OF MANUFACTURE

Leo T. Meister, Irvington, N. J.

Application November 9, 1945, Serial No. 627,770

1 Claim. (Cl. 86—20)

(Granted under the act of March 3, 1883, as amended April 30, 1928; 370 O. G. 757)

1

The invention described herein may be manufactured and used by or for the Government for governmental purposes without the payment to me of any royalty thereon.

My invention relates to improvements in artillery ammunition primers, and in the method or process of manufacturing them.

An important object of my invention is to provide an artillery ammunition primer in which the interior liner for the igniter charge tube containing the flash or flame holes is formed of a fusible thin-walled metallic seamless tube closed at one end and all formed of one integral piece of metal, as for example, by a drawing operation. Closed and seamless tubes of the type referred to above resemble an elongated sewing thimble having cylindrical walls, and are referred to herein and in the appended claims as "thimbles."

These thimbles may be made of any easily fusible suitable metal which is subject to plastic flow in drawing and which may be easily creased or folded at the open end, and said folded end, upon the application of pressure, being capable of forming an effective seal against the harmful influence of air, gases and moisture as hereinafter more fully appears. Such thimbles may be advantageously formed of tin or lead, or alloys of tin and lead, said alloys consisting, for example, of 50% tin and 50% lead, or 60% lead and 40% tin. In the further description which follows, it may be assumed that these thimbles are made of, or drawn from an alloy of tin and lead, it being understood, however, that the naming of these metals and/or alloys is to be considered as words of inclusion and not of limitation, as will be understood by a person skilled in the art. Thimbles formed of alloys of lead and tin have proved to be very satisfactory in the practice of the invention.

A further object of my invention is to provide an artillery primer in which a thimble liner as heretofore described may be closed and sealed against all harmful influence of air, gases and moisture without the use of an added sealing agent so that the primer, while simple in construction, will be efficient in operation.

Other objects and advantages of the invention will become apparent during the course of the following description.

The accompanying drawings, forming part of the specification, illustrate the manner in which I attain these objects. Similar numbers are used to designate like parts throughout the specification and drawings. In these drawings:

2

Figure 1 is an elevation in perspective of one of the thimbles;

Figure 2 is a longitudinal central section of an igniter charge tube;

Figures 3 to 6, inclusive, show longitudinal central sections of the igniter charge tube after the thimble has been positioned therein, and illustrate the successive steps by which the objects of the invention are attained;

Figure 3 shows the thimble in section in place within the tube;

Figure 4 shows the thimble in section with the igniter charge in place within the thimble;

Figure 5 shows the thimble in elevation after mechanical or manual closing of the open end of the thimble;

Figure 6 shows an elevation of the closed thimble being forced against the igniter charge within the igniter charge tube;

Figure 7 is an elevation, partly in section, of an artillery ammunition primer manufactured according to the invention, including a partial section of the head containing the cup for holding the usual percussion elements;

Figure 8 is an elevation in perspective of a thimble containing an igniter charge as included in Figure 5 showing one method of closing the top by folding before forcing down against the igniter charge.

Referring now in detail to the accompanying drawings, the numeral 10 indicates a thin walled tin-lead alloy thimble as described and defined above, the numeral 11 indicates an igniter charge tube, and numeral 12 indicates the head at the firing end of the tube 11. Head 12 carries a suitable percussion element 12a for igniting the igniting charge hereinafter mentioned. Head 12 is attached to the igniter charge tube 11 by a portion of the former engaging with screw threads 13 within igniter tube 11. The head 12 engages with the tube 11 tightly, and preferably tight enough that there is air tight engagement or connection between the head 12 and the igniter tube 11. As shown, igniter charge tube 11 is provided with a number of vents or flame holes 14 for the passage of flame arising from the igniter charge when the primer is fired. The igniter tube 11 is advantageously made of brass.

50 The thimble 10 is located within the igniter charge tube 11. This thimble fits closely within the interior of the igniter charge tube 11 and covers all of the flame holes 14 thereof. The closed end of the thimble abuts against the closed end 15 of the igniter charge tube 11. The

thimble 10 is made long enough so that its open end will extend above the top of the igniter charge tube 11 a distance sufficient to permit the walls of the open end to cover the entire opening when folded upon itself, and slightly smaller in diameter than the interior diameter of the igniter charge tube 11 so that it may be inserted easily with a sliding fit within igniter tube 11, and into the position shown in Figures 3 to 6, inclusive, so that the walls of the thimble 10 abut against the interior walls of the igniter tube 11.

In loading the primer, a black powder charge or other igniter charge 16 is inserted into the thimble 10 after it has been inserted into position as shown in Figure 3, filling the said thimble 10 to the approximate level of the bottom of the screw threads 13, thus providing an unfilled air space of the approximate height of the distance between the bottom of said screw threads 13 and the top of the tube 11 after the closing of the thimble 10. Thereupon, the walls of the open end are folded inwardly, in a manner similar to that used in closing the open end of a filled bag or package, using either mechanical or manual means, so that the now closed top of the thimble 10 is approximately even with the open top of the igniter tube 11, as shown in Figure 5. After the thimble 10 has been closed as described above, the closed top and the walls of the hollow air space are pushed downward within the thimble 10 as shown in Figure 6, by either mechanical or manual means, against the top of the igniter charge 16, thus completely sealing the thimble 10, and sealing the perforations 14. Such means may consist of a rammer 17 as shown in Figures 5 and 6. When the head 12 containing the percussion elements is screwed in tight engagement with screw threads 13, the primer is ready for use in connection with fixed, semi-fixed or separate loading ammunition. The striking of the percussion cap or element in the head 12 produces a flame which ignites the igniter charge of black powder or other igniter charge 16 which has been placed within the fusible thimble 10. The burning of the igniter charge produces flame which meets the fusible thimble and this flame passes to the exterior of the igniter charge tube 11.

through the openings 14 and ignites the explosive or propellant charge in connection with which the primer herein described is used.

A fold similar to the closure of an envelope is shown in Figure 8 and described above as a method of closing the top of the thimble 10. Closure as contemplated by the invention may be obtained by pinching and creasing the end of the thimble 10, by making a triangular fold after the thimble end has been pressed flat, or by any other method effectively closing the top of the thimble.

From the foregoing it will be apparent that the thimble 10 may be formed of any metal that is readily fusible by the heat or flame produced by the burning of the igniter charge. There is, however, further advantages in using thimbles formed wholly or in part of tin, or comprising tin as a component of the metal thereof, because of the products resulting from the destruction of the thimble by the burning of the igniter charge promotes or causes decoppering of the bore of the cannon.

Having thus described my invention, I claim:

A method of manufacturing a primer which comprises placing a thin-walled metallic thimble into an igniter charge tube in bottom engagement therewith, placing an igniter charge in the thimble, and sealing the igniter charge within the thimble by folding the open end walls of the thimble upon themselves, forcing the closed end thus formed into the tube and against the igniter charge and expanding said thimble in said tube.

LEO T. MEISTER.
